UNITED STATES PATENT OFFICE.

HARRY L. MULLEN, OF BALTIMORE, MARYLAND.

FUNNEL.

Application filed February 3, 1923. Serial No. 616,719.

To all whom it may concern:

Be it known that I, HARRY L. MULLEN, a citizen of the United States, residing in the city of Baltimore and State of Maryland, have invented certain new and useful Improvements in Funnels, of which the following is a specification.

My present invention is a funnel intended more particularly for use in filling the radiators of automobiles, and the object of the invention is to produce a funnel which may be used upon the filling collar of any radiator and be firmly supported in position thereon. The invention resides in certain novel features which will be hereinafter fully set forth.

In the drawing:

Figure 1 is a front elevation of my improved funnel in operative position;

Fig. 2 is a transverse section on the line 2—2 of Fig. 1, and

Fig. 3 is a detail view showing parts of the retaining devices in perspective and in disassembled relation.

The body 1 of the funnel is preferably elliptical at its upper end and tapers to and terminates in a circular nozzle or spout 2. The body is preferably made of sheet metal and at the juncture of the body with the nozzle or spout, I provide a screen or filter 3. Upon the sides of the body, I secure base plates 4 having their lower ends arranged immediately adjacent the upper end of the nozzle or spout 2 and provided at their said lower ends with lugs or ears 5. Clamping members 6 are pivotally supported upon the base plate 4 by pivot pins 7 inserted through the lugs or ears 5 and similar lugs or ears 8 upon the clamp-

ing member, and it will be readily noted that a clamping member is provided upon each side of the funnel. Springs 9 are coiled around the pivot pins 7 and have their ends bearing upon or secured to the base plates 4 and the clamping members 6, respectively, so that they normally hold the lower ends of the clamping members to the spout 2, as will be readily understood upon reference to Fig. 2. The upper ends of the clamping members 6 are curved outwardly, as shown at 10, to provide convenient thumb pieces and their lower ends are projected inwardly, as shown at 11, to form stops or

jaws adapted to bear against the spout or nozzle. A jaw 12 consisting of a bowed resilient strip of metal is secured upon the inner face of each clamping member 6 at the lower end thereof and rests upon the stop 11, as shown. This resilient jaw is adapted to fit around the filling collar 13 of a radiator 14, and its bowed shape, together with its resilient quality, will permit it to easily engage collars of various diameters so that a single nozzle may be used upon a wide range of radiators.

When a radiator is to be filled, the closure of the radiator collar is removed and my improved funnel is placed in position upon the collar with the nozzle or spout 2 fitting within the same. To place the funnel in position, a slight pressure is exerted upon the upper ends of the clamping members 6 so that the lower ends thereof and the jaws 12 carried thereby will be moved away from the nozzle or spout 2 a sufficient distance to permit the nozzle or spout to enter the filling collar of the radiator with the clamping members at the outer side of the collar. When the pressure upon the upper ends of the clamping members is relieved, the springs bearing upon said members will swing them into engagement with the radiator collar so that the funnel will be firmly supported and will not require attention on the part of the user. The radiator may then be filled without any liability of the funnel being displaced. My improved device is exceedingly simple and inexpensive, may be very easily applied to or removed from a radiator filling collar and will be found highly efficient for the purpose for which it is designed.

Preferably, the external diameter of the nozzle is less than the internal diameter of the radiator collar so that an open space 95 is left between them. By watching this space, the operator is enabled to avoid overflowing.

Having thus described the invention, what is claimed as new is:

1. A funnel provided with a nozzle, a clamping member pivotally mounted upon the side of the funnel and having its lower end provided with an inwardly projecting jaw and disposed adjacent the nozzle, and yieldable means secured between the side of

the funnel and the said member and holding the jaw at the lower end thereof normally against the side of the nozzle.

2. A funnel provided with a nozzle, a clamping member pivotally mounted upon the side of the funnel, a resilient bowed jaw carried by the lower end of the clamping member and extending laterally beyond the

side edges thereof, and a spring secured between the funnel and the clamping member and acting upon the clamping member whereby to hold the said jaw normally toward the nozzle.

In testimony whereof I affix my signature.

HARRY L. MULLEN. [L.S.]
